Primary Examiner — Zenia Bennett(57) **CLAIM**

The ornamental design for a hair coloring device, as shown and described.

DESCRIPTION

FIG. 1 is a front elevational view of a hair coloring device showing an embodiment of my design;

FIG. 2 is a back elevational view of a hair coloring device;

FIG. 3 is a left side elevational view of a hair coloring device;

FIG. 4 is a right side elevational view of a hair coloring device;

FIG. 5 is a top plan view of a hair coloring device;

FIG. 6 is a bottom plan view of a hair coloring device;

FIG. 7 is a front perspective view of a hair coloring device; and,

FIG. 8 is a front elevational view of a hair coloring device being used on a head of a human.

The broken lines used on the head, hand, and arms in the drawings are for illustrative purposes only and form no part of the claimed design.
